CLAIM

The ornamental design for a cigar-shaped pen, as shown and described.

DESCRIPTION

FIG. 1 is a front elevational view of a cigar-shaped pen showing my new design;

FIG. 2 is a rear elevational view thereof;

FIG. 3 is a left side elevational view thereof, the opposite side being a mirror image thereof;

FIG. 4 is a front elevational view similar to FIG. 1 with the pen open and the cap placed on a bottom end thereof; and, FIG. 5 is a top plan view thereof.

The file of this patent contains at least one drawing executed in color. Copies of this patent with color drawing(s) will be provided by the Patent and Trademark Office upon request and payment of the necessary fee.
